BASCUM O. AUSTIN, OF EAST PITTSBURGH, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed June 23, 1925. Serial No. 38,982.

My invention relates to control apparatus and more particularly to apparatus for controlling alternating-current circuits.

The object of the invention, generally stated, is the provision of an overload trip device that shall be simple and efficient in operation, and readily and economically manufactured.

A more specific object of the invention is to provide for damping the movements of the armature of an alternating-current relay that is disposed to effect the actuation of the switch member of an overload trip device upon the flow of a predetermined current.

Other objects of the invention will in part be obvious and in part appear hereinafter.

The invention, accordingly, is disclosed in the embodiment thereof shown in the accompanying drawing and comprises the features of construction, combination of elements and arrangement of parts which will be exemplified in the construction hereinafter set forth and the scope of which will be indicated in the claims.

For a fuller understanding of the nature and objects of the invention, reference should be had to the following detailed description, taken in connection with the accompanying drawing in which,

Figure 1 is a plan view of an overload trip device constructed in accordance with this invention, showing the armature of the alternating-current relay locked against operation,

Fig. 2 is a plan view, similar to that shown in Fig. 1, showing the armature of the alternating-current relay released,

Fig. 3 is a diagrammatic view showing the overload trip device connected to limit the flow of current in an alternating-current circuit,

Fig. 4 is a view, partially in section and partially in elevation, of a portion of the apparatus shown in Figs. 1 and 2, and

Fig. 5 is a view in end elevation of the part shown in Fig. 4.

Referring now to the drawing, a casting 10, which is of some material capable of conducting electricity is mounted on a base 11 that serves as an insulator. As will be observed, the casting 10 is provided with an upper bracket 12 for supporting a part

of the control apparatus by means of screw bolts.

An alternating-current relay 13 of any suitable type is mounted on the bracket 12. In this particular construction, the relay includes a vertically disposed coil 14, which is provided with terminals 15 and 16 for connecting it in an alternating-current circuit. An armature 17 is pivotally mounted on a pin 18, which is carried by the frame of the relay 13 and is disposed for actuation by the coil 14.

In order to actuate or position the armature 17 when the coil 14 is deenergized, a vertically extending coil spring 20 is interposed between the armature and a bracket 19 that is mounted on the casting 10. As shown, an adjustable connection 21 in the form of a set screw is mounted on the bracket 19 to engage the end of the spring 20. Accordingly, by adjustment of the set screw 21, the tension of the spring 20 may be varied as desired to restrict the functioning of the relay until a predetermined current flows in the controlling circuit.

With a view to damping the movements of the armature 17 of the alternating-current relay, a direct-current relay 22, which may be energized from any suitable source, is horizontally disposed on the casting 10 just below and to the left of the alternating-current relay 13, as shown in Figs. 1 and 2. In this particular construction, the relay frame is provided with lugs 23 which may be attached to the casting 10 by means of screw bolts 24.

As will be noted, the relay 23 comprises a coil 25 that is provided with terminal 26 for connecting it to any suitable source of direct-current supply.

An upwardly-extending armature 27, which is pivotally mounted on a pin 28 that is carried by the frame of relay 22, is disposed in alignment with the coil 25. As shown, lateral extension or arm 29 is provided on the armature 27 and is adapted for use in the making and breaking of a circuit, as will be set forth hereinafter.

In this particular construction, the extension 29 is disposed at substantially right-angles to the armature 27. A vertically disposed coil spring 30, one end of which is adjustably connected to a bracket 31 that is carried by the relay frame, has its other

end connected to the extension 29. It will be readily understood that this spring may be placed under sufficient tension, by means of an adjusting device 30^a, to assure the 5 clockwise rotation of the armature 27 about its pivot point 28 when the coil 25 is de-energized.

In order to utilize the armature 27 to damp the movements of the armature 17, an 10 insulating block 32 is provided for establishing engagement between them. As will be observed, the block 32 is attached to the armature 17 and depends below the end of the armature 27.

15 The block 32 has a notch 33 cut therein for the reception of the end of the armature 27. Furthermore, a vertical face 34 is presented by block 32 for engaging armature 27 when both relays are deenergized and 20 the armature 17 is drawn to its lowermost position. The block 32 is so positioned that when the armature 27 rests against the face 34, the extension 29 or a contact member mounted thereon, is retained in engagement 25 with a stationary contact member 35, which is adjustably disposed on a bracket 36 that is attached to the lower end of the casting 10.

30 In order to maintain electrical connection between the extension 29 and the contact member 35, a resilient contact plate 37 is attached to the former, as best shown in Fig. 4. As will be noted, the contact plate 37 is disposed on the upper face of the extension 35 29 to overlie an opening that is provided in the extension for the reception of the contractor 35.

40 Referring now to Fig. 3, a switch 38 is shown connected in a supply circuit 39. In this particular construction, the switch 38 includes a plurality of contact members 43 disposed in the respective circuit conductors. In order to actuate the contact members 43, a pair of jointed members or links 40 are 45 actuated to effect the opening of the switch 38 by a spring 41 and to effect the closure of the switch by an electromagnet 42.

50 A storage battery 44 may be connected across the actuating coil 25 of the direct-current relay 22 to effect the energization of the latter. As shown, a push-button 45 is connected in the circuit of the actuating coil 25 to provide for the energization of the latter as desired. The actuating coil of the 55 electromagnet 42 is connected across the battery 44 through the casting 10, the extension 29 of the armature 27 and the contact member 35. The alternating-current relay coil 14 is connected across the secondary coil of a series transformer 46 that is connected in the line 39. As is usual practice, the introduction of the transformer 46 assures greater 60 sensitivity of the relay.

65 Assume that the coil 25, of the direct-current relay 22 has been energized through

push-button 45 to actuate the armature 27 to close the circuit of the actuating coil of the electromagnet 42, thereby closing the switch 38. The armature 17 is then released from the armature 27 and is drawn to its 70 lowermost position by the spring 20, as shown in Fig. 2. Upon the release of the push-button 45, the armature 27 is permitted to rotate about its pivot point 28 under the action of the biasing spring 30. In this manner the armature is projected against the face 34 of the block 32.

75 Assume that the current flowing in the line 39 is increased to a predetermined value sufficient to effect the operation of the relay 80 13. The coil 14 is then sufficiently energized to raise the armature 17, thereby releasing the armature 27. As soon as the armature 27 is released, it is rotated about its pivot point 28 by the spring 30, projecting its 85 upper end into the notch 33 of the block 32, as illustrated in Fig. 1. Accordingly, the armature 17 is locked in its raised position. Its movements are thus damped by the armature 27, which first rides on the face 34 90 and then engages the notch 33 of the block 32.

95 It will be evident that when the armature 27 is rotated to separate the plate 37 and contact member 35, the switch actuating coil 42 is deenergized and the switch is opened by the spring 41. In this manner the circuit 39 may be opened when the current therein reaches any predetermined value.

100 In order to reset the relay 13, the push-button 45 is operated to effect the energization of coil 25. Upon the energization of coil 25 the armature 27 is actuated to close the circuit of the actuating coil 42, which effects the closure of the switch 38.

105 As will be readily understood, whenever the push-button 45 is released, the armature 27 will rotate through a predetermined angle under the action of the spring 30 until its upper end again engages the face 34 of the 110 block 32. During such rotation of the armature, the resilient contact plate 37 maintains electrical connection with the contact member 35, thereby maintaining the energizing circuit of the actuating coil of the 115 switch 38.

120 Since various changes may be made in the above-described connections and arrangement of parts, and different embodiments of the invention may be made without departing from the scope thereof, it is intended that all matter contained in the above description or shown in the accompanying drawing shall be interpreted as illustrative and not in a limiting sense.

125 I claim as my invention:

1. An overload trip device for an alternating-current circuit comprising, in combination, an alternating current relay provided with a movable armature, said relay being 130

adapted to actuate the armature upon the flow of a predetermined current in said circuit, a direct-current relay provided with a spring-biased armature and means for energizing the direct-current relay to actuate its armature against the action of the spring, said armatures being disposed to engage one another, said spring-biased armature being disposed to dampen the movements of the alternating-current relay armature when the direct-current relay is deenergized, the alternating-current relay armature being provided with a notch to receive the spring-biased armature to effect the locking of one of the armatures in a predetermined position.

2. An overload trip device for an alternating-current circuit comprising, in combination, an alternating-current relay provided with a movable armature and adapted to actuate the armature upon the flow of a predetermined current in said circuit, a direct-current relay provided with a spring-biased armature and means for energizing the direct-current relay to actuate its armature against the action of the spring, said armatures being disposed to engage one another, the direct-current relay when energized being adapted to retain its armature out of engagement with the alternating-current relay armature to permit free movement of the latter.

3. An overload trip device for an alternating-current circuit comprising, in combination, an alternating-current relay provided with a movable armature and adapted to actuate the armature upon the flow of a predetermined current in said circuit, a switch for controlling the flow of current in the alternating-current relay, an actuating

coil for said switch, a direct-current relay provided with a spring-biased armature and means for energizing the direct-current relay to actuate its armature, said armatures being disposed to engage one another, the spring-biased armature being disposed to control the flow of current in the switch-actuating coil, said alternating-current relay armature being disposed to retain the spring-biased armature in a position to maintain the switch-actuating-coil circuit.

4. An overload trip device for an alternating-current circuit comprising, in combination, an alternating-current relay provided with movable armature and adapted to actuate the armature upon the flow of a predetermined current in said circuit, a switch for controlling the flow of current in the alternating-current relay, an actuating coil for the line switch, a direct-current relay provided with a spring-biased armature and means for energizing the direct-current relay to actuate its armature, said armatures being disposed to engage one another, the spring-biased armature being disposed to control the flow of current in the switch-actuating coil, said alternating-current relay armature being disposed to retain the spring-biased armature in a position to maintain the switch-actuating-coil circuit, and a resilient contact member carried by the spring-biased armature, said contact member serving to maintain the switch-actuating-coil circuit during a predetermined angular movement of the direct-current relay armature.

In testimony whereof, I have hereunto subscribed my name this 4th day of June, 1925.

BASCUM O. AUSTIN.
